Montgomery Ward
ATTORNEYS

UNITED STATES PATENT OFFICE.

LEON DE FERNELMONT, OF CLIFTON, NEW JERSEY.

DENTAL APPLIANCE.

Application filed March 16, 1923. Serial No. 625,576.

To all whom it may concern:

Be it known that I, LEON DE FERNELMONT, a citizen of the United States, and resident of Clifton, in the county of Passaic and 5 State of New Jersey, have invented a new and useful Improvement in Dental Appliances, of which the following is a specification.

In dental work when it was desired to 10 melt wax for various purposes as, for instance, for affixing artificial teeth in place on plaster models, it has been the custom to pick up a small quantity of solid wax on the end of a spatula, hold it in the flame of 15 a Bunsen burner until the wax was melted and then to flow the wax over the required part of the tooth and model. It oftentimes happens that the wax while being so held in the flame would drop off from the spatula 20 into the burner and thereby clog up the gas opening therein. This method of melting the wax was slow, uncertain and time consuming.

The object of my invention is to eliminate 25 these disadvantages by the provision of a dental appliance including a heating tray for the wax, which tray surrounds the flame tube of the burner and may be adjusted upwardly and downwardly along the flame 30 tube toward and away from the flame, where by a greater or lesser amount of heat may be conducted from the flame tube to the tray for melting the wax to the desired condition.

Practical embodiments of my invention 35 are represented in the accompanying drawings, in which—

Fig. 1 represents my dental appliance in top plan.

Fig. 2 represents the same in side elevation.

Fig. 3 represents a vertical transverse section taken in the plane of the line III—III of Fig. 2.

Fig. 4 represents a detail view partly in 45 side elevation and partly in section, showing a modified form of heating tray.

The Bunsen burner in connection with which my invention is illustrated may be of the well known type in which the base 50 is provided with the usual gas inlet tube 2

and the upright flame tube 3.

The tray for holding the wax to be melted is denoted by 4 and it may be made of sheet metal or other suitable heat conducting material. This tray is provided with a centrally arranged sleeve 5 which is of the required shape and size to snugly embrace the flame tube 3 and to serve as a medium for conducting the heat from the flame tube to the tray for melting the wax to a greater 55 or lesser extent. The sleeve 5 of the tray uprises from the bottom thereof a sufficient distance to keep the wax from contact with the flame tube.

The tray may be moved upwardly and 60 downwardly along the flame tube toward and away from the flame to different positions for causing a greater or lesser amount of heat to be conducted from the flame tube to the tray for more or less melting the wax 65 contained therein. The tray may be held in its adjusted positions by the frictional contact of the sleeve with the flame tube. If so desired, the sleeve may be provided with a split portion for this purpose. In Figs. 70 1 to 3 inclusive the split portion, denoted by 6, is located at the upper end of the sleeve. In Fig. 4 I have shown the split portion 7 in the lower end of the sleeve which, in this instance, depends from the bottom of the 75 tray.

In practice I preferably provide two of 80 these trays so that the wax in the two trays may be subjected to different degrees of heat. I have shown the lower tray as greater 85 in diameter than the upper tray. It will be seen that the wax in the lower tray will be melted to a lesser degree than the wax in the upper tray. This is very desirable under certain conditions where larger quantities of the wax of semi-liquid form are needed at one time than could be obtained from the upper tray. This lower tray may also be used as a reserve container for supplying 90 wax to the upper tray, when so desired.

It is evident that my appliance may be used for melting other materials than wax and that it could be used in connection with other types of burners than Bunsen burners.

It is also evident that various changes may 100

be made in the construction form and arrangement of the several parts without departing from the spirit and scope of my invention; hence, I do not wish to be limited to the particular embodiments herein shown and described, but

What I claim is:—

1. In a dental appliance, a burner comprising a suitable base having a gas inlet tube and upright flame tube, and a heating tray surrounding and adjustable upwardly and downwardly along the flame tube toward and away from the flame.
- 10 2. In a dental appliance, a burner comprising a suitable base having a gas inlet tube and an upright flame tube, and upper and lower heating trays surrounding and adjustable upwardly and downwardly along the flame tube toward and away from the flame.
- 15 3. In a dental appliance, a burner comprising a suitable base having a gas inlet

tube and upright flame tube, and a heating tray surrounding the flame tube and provided with a sleeve frictionally embracing said flame tube for adjustably positioning the tray upwardly and downwardly along the tube toward and away from the flame.

25 4. In a dental appliance, a burner comprising a suitable base having a gas inlet tube and upright flame tube, and a heating tray surrounding the flame tube and provided with a sleeve frictionally embracing said flame tube for adjustably positioning the tray upwardly and downwardly along the tube toward and away from the flame, 30 said sleeve uprising from the bottom of the tray a sufficient distance to keep the contents of the tray from contact with the flame tube.

35 In testimony that I claim the foregoing is my invention, I have signed my name this 15th day of March, 1923.

40 LEON DE FERNELMONT.
